Atty's.

UNITED STATES PATENT OFFICE.

NILS GUSTAF LARSON, OF ATTLEBORO, MASSACHUSETTS, ASSIGNOR TO AMES SHOVEL & TOOL COMPANY, OF JERSEY CITY, NEW JERSEY, A CORPORATION OF NEW JERSEY.

REINFORCE DEVICE FOR TOOL HANDLES AND PROCESS OF MAKING THE SAME.

Application filed January 4, 1922. Serial No. 610,728.

To all whom it may concern:

Be it known that I, NILS GUSTAF LARSON, a citizen of the United States of America, and resident of Attleboro, in the county of 5 Bristol and State of Massachusetts, have invented new and useful Improvements in Reinforce Devices for Tool Handles and Processes of Making the Same, of which the following is a specification.

This invention pertains to tool handles and relates more particularly to metallic reinforcing devices for wooden handles of the D-type and to a process of making such devices.

Handles for shovels, spades and similar tools usually comprise a wooden haft which is split at its upper end to provide a fork whose sides or tines are spaced apart and held in diverging relation by means of a

grip bar inserted between their ends. Commonly a rod extends axially through the grip bar and through the tines of the fork, and is headed over at its opposite ends to secure the parts in operative relationship.

In order to prevent splitting of the ends of the grip bar under the strain of use it is common to encircle its ends with metallic rings or ferrules and in some instances these rings or ferrules have been combined integrally or otherwise with cap members enclosing the joints between the ends of the grip bar and the side members of the handle, and with attaching brackets or braces extending lengthwise of the handle mem-

bers for distributing the strain longitudinally thereof. When these several elements have been integrally united no practical method has heretofore been known by which the ring or ferrule could be formed with- 40 cut joint or seam and even though care be exercised in uniting, as by welding, the ends of those portions of the blank composing the ring, the completed ring is not as strong as a seamless ring would be and often opens 45 at the joint. The rod extending through the bar is thus called upon to support the entire force applied to the grip bar and under this stress frequently bends, splitting the grip bar and ruining the handle.

The principal object of the present invention is to provide a metallic reinforcing device comprising in a single unitary struc-

ture a seamless ferrule adapted to prevent splitting of the end of the grip bar, a cap for covering the end of the fork member and the joint between the latter and the grip bar, and an attaching member or bracket extending lengthwise of the fork member, together with a novel form of blank from which such reinforcing device may be made and a novel process of manipulating the blank to produce the finished article. In the accompanying drawings there is illustrated by way of example a preferred form of blank useful in constructing a reinforcing device in accordance with the present invention, together with certain stage products illustrating the various steps comprised in such process, and also the finished article as applied to a tool handle. In such drawings:

Fig. 1 is a plan view of a sheet metal blank of preferred form;

Fig. 2 is an edge view of the blank;

Fig. 3 is a front elevation showing the blank after the performance of the first steps in the operation;

Fig. 4 is a transverse cross section on the line 4—4 of Fig. 3;

Fig. 5 is a side elevation of the device shown in Fig. 3;

Fig. 6 is an end elevation showing the device at the end of the next following step in the operation;

Figs. 7 and 8 are front side elevations respectively showing the blank at the completion of the next step in the process;

Figs. 9 and 10 are front and side elevations respectively showing the completed device; and

Fig. 11 is a fragmentary perspective view showing the upper end of a tool handle of D-form having the reinforcing device of the present invention applied thereto.

In accordance with the present invention the preferred form of blank, as shown in Figs. 1 and 2, is formed from sheet material such as steel by a stamping or punching operation. This blank is of broadly spatulate form, comprising the head portion 1, and the elongate shank portion 2. The head portion terminates in an arcuate edge 3 and is provided with straight diverging lateral edges 4, 5, substantially tangent

to the circle of which the edge 3 forms an arc. The extremities of the curved end 3 do not however, directly merge with the sides 4, 5, but are separated therefrom by 5 ears 6, 7 outstanding from opposite edges of the blank. These ears comprise the laterally extending straight edges 8, 9 respectively, the sides 10, 11 which are substantially parallel respectively with the edges 4, 10 5 of the head proper, and the curved portions 12, 13 uniting such straight edges 10, 11 with the edges 4, 5 of the head. The shank is provided with substantially parallel lateral edges 14, 15 which are united 15 with the extremities 16, 17 of the diverging straight edges 4, 5 of the head by the curved elements 18, 19. The outer ends of the edges 14, 15 are united by the curved edge 20 constituting the end of the shank. As the 20 shank is narrower than the head this edge 20 may be of shorter radius than the curved end 3 of the head.

The blank thus formed is subjected to the action of suitable dies or other forming 25 tools which bend the shank and head transversely into trough-like form, giving such shank and head a substantially cylindrical curvature. The material of the end portion of the head 1 is so worked as to form 30 a cup having a substantially flat circular bottom 21 lying in a plane perpendicular to the plane of the original blank and whose side walls are formed by the flange, as defined by the broken line $x-y$, Fig. 5, comprising the portion 22 forming an integral continuation of the head 1, and a portion 35 23 which extends from the edge 9 of one ear to the edge 8 of the other. The portion 22 of this flange properly constitutes a 40 part of the head 1, but for convenience in description is herein referred to as included in the flange. By reason of the greater width of the head 1 than the shank 2, the sides of the cylindrically curved trough 45 like structure resulting from the operations just described will be deeper at the head portion of the device than in the shank portion thereof. During the process of forming the cup the metal of the head flows 50 to such an extent that the edges 4, 5 of the head are brought into substantial parallelism.

The next step in the operation consists in 55 removing the entire bottom 21 of the cup to leave the opening 24, this operation being performed by punching or other suitable process. In Fig. 6 the device is shown in end view after the completion of this step 60 of the process, the side walls only of the cup remaining and forming the continuous seam less ring 25 comprising the portions 22 and 23 of the flange previously described. The opening 24 thus formed is of substantially the diameter of the grip bar of the 65 handle to which the device is to be applied

and the ring 25 thus constitutes a seamless ferrule for encircling such bar.

After the bottom of the cup has been removed, its side walls, together with adjacent portions of the head 1, are subjected 70 to a further operation by means of dies or other suitable devices whereby the ring 25 is caused to lie in a plane substantially parallel to the plane of the original blank, thus forming the cap 26 as shown in Fig. 8. 75 During this operation the edges 10, 11 of the ears 6, 7 are brought into engagement with portions of the edges 4, 5 respectively of the head of the blank, and while the abutting edges may if desired be welded, 80 this is not necessary, as no substantial strain is imposed upon the completed device when in use such as would tend to separate the abutting edges. In thus bringing the ring 25 into parallelism with the shank portion 85 of the flange, the width of the ears 6, 7, as defined by the edges 8, 9, serves to determine the spacing of the portion 23 of the ring from adjacent portions of the shank, leaving an opening 27 between the part 23 90 and the shank of sufficient size to admit the end of a tine of the forked portion of the tool handle.

After the above operation has been completed the device is subjected to the action 95 of dies, punches or other suitable tools which bend the shank portion 2 in a longitudinal direction, as indicated in Fig. 10 to conform to the curvature of the outer face of the tine member of the tool handle, 100 while openings 28, 29 are formed in the head and shank portions respectively for the reception of fastening devices.

The completed reinforcing device shown 105 in Figs. 9, 10 and 11 is applied to a handle as illustrated in Fig. 11. In this view the haft of the handle is indicated at 30, such haft being bifurcated or split at its upper end to form the fork comprising the tines 30^a, 30^b, which are held in spaced diverging relation by means of the grip bar 31 interposed between their free extremities. A reinforcing device constructed in accordance with the present invention is applied 110 to the upper end of each fork member in such manner that its cap portion 26 covers and encloses the upper end of the corresponding fork member while the flange portion of such cap, comprising the element 23 encircles the grip member and constitutes a ferrule for preventing splitting 115 thereof. The shank portion of the device extends downwardly along the fork member and may be secured thereto by means of a fastener 33 extending through the opening 29. A rod 32 passes through the opening 28 and axially through the grip bar 31 and thence outwardly through the corresponding opening of the opposite reinforcing device, such bar being preferably 120

riveted over at its opposite ends to secure the parts in operative relationship. As thus constructed the reinforcing device is integral and seamless, and the ferrule forming a portion thereof is sufficiently strong to withstand any strain to which it may be subjected without danger of opening or breaking. The attaching brackets being integral with the caps 26 serve to distribute the strain imposed upon the latter over a considerable area of the fork member, and as the device is in one piece, it requires a minimum amount of labor to apply it to the handle. In accordance with the process as described, the reinforcing device may be made very cheaply and requires no welding operation for securing its several parts together. While the blank shown in Fig. 1 is preferred, it is contemplated that slight variations in the shape of the blank might be made without substantially affecting the process involved in producing the finished device, and without substantial variation in the shape of the device as completed.

I claim:

1. A reenforce device for tool handles of that type having diverging side members spaced at their ends by an interposed grip bar comprising a seamless sheet metal ferrule for the reception of the end of the grip bar, and an elongate attaching bracket integrally united to the ferrule and shaped to fit against the side member of the handle.

2. A reenforce device for tool handles of that type having diverging side members spaced at their ends by an interposed grip bar comprising an integrally continuous sheet metal ferrule member for the reception of one end of the grip bar, a cap integral therewith for covering the joint between the grip bar and the side member of the handle, and an attaching bracket integral with the cap and depending therefrom, said attaching bracket being shaped to fit against the side member of the handle.

3. A reenforce device for tool handles of that type having diverging side members spaced at their ends by an interposed grip bar, comprising a cap portion adapted to embrace the end of one of the side members of the handle and to cover the joint between the latter and the grip bar, a seamless sheet-metal ferrule integral with the cap for embracing the end of the grip bar, and an elongate attaching bracket integral with the cap and of proper shape closely to conform to the outer surface of the handle member.

4. That stage product in the production of reenforce devices for tool handles comprising an axially narrow cylindrical sheet-metal ring having spaced ears projecting axially from one edge, and a trough-like part having walls forming an integral continuation of the edge of the ring between

said ears, that portion of the trough-like part remote from the ring being shallower than at that portion where it joins the ring.

5. That process of making reenforce devices for tool handles which comprises as steps, forming an elongate blank from sheet material, working the material at one end of the blank to form a flat bottomed cup having its bottom perpendicular to the axis of the shank and a portion of its side wall in integral continuation of the adjacent part of the blank, removing the flat bottom of the cup to leave a circular opening, and bending the wall portion of the cup to lie in a plane parallel to the plane of the original blank.

6. That process of making reenforce devices for tool handles which comprises as steps, forming a blank from sheet material, working the material at one end of the blank to provide a cup having its bottom lying in a plane perpendicular to the plane of the original blank, removing material from the bottom of the cup to leave a circular opening, and bending the remaining material of the cup to bring the plane of said opening into parallelism with the plane of the original blank.

7. That process of making reenforce devices for tool handles which comprises as steps, forming an elongate blank from sheet material of greater width at one end than at the other, the wider portion being curved at its end and having ears outstanding from its opposite edges and defining the extent of said curved end, bending said blank into transversely curved trough-like form and working the material at the wider end of the blank to form a cup having its bottom perpendicular to the axis of the blank and with the curved end of the blank forming a flange member constituting the wall of the cup between the lateral edges of the blank end and in integral continuation of the latter, removing material from the bottom of the cup to leave a seamless ring, and bending the wider end of the blank including said ring and the ears until such ears engage the adjacent edges of the blank and the ring is brought into parallelism with the plane of the original blank with its edge spaced from the main body of the blank by the width of said ears.

8. That process of making reenforce devices for tool handles which comprises as steps, forming a sheet metal blank having head and shank portions, the head portion having a curved end defined by ears outstanding from opposite edges of the blank, subjecting the blank to pressure to impart a cylindrically curved trough-like form thereto, and to form the end portion of the head into a flat bottomed cup having its bottom substantially perpendicular to the axis of the blank and provided with a flange.

connecting the opposite edges of the blank, punching out the bottom of the cup, bending the cup portion of the head to lie in a plane substantially parallel to the plane of the original blank until the edges of the outstanding ears contact with adjacent edges of the head, bending the shank portion in a

longitudinal direction, and forming openings in the head and shank respectively for the reception of fastening devices.

10

Signed by me at Attleboro, Massachusetts, this 30th day of December, 1922.

NILS GUSTAF LARSON.
